UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-SIGNAL.

1,307,741.

Specification of Letters Patent. Patented June 24, 1919.

Application filed August 2, 1918. Serial No. 248,063.

To all whom it may concern:

Be it known that I, LLOYD V. LEWIS, a citizen of the United States, residing at Edgewood borough, in the county of Allegheny and State of Pennsylvania, have invented certain new and useful Improvements in Railway-Signals, of which the following is a specification.

My invention relates to railway signals; 10 and particularly to signals of the type comprising a semaphore biased to the "stop" position, a motor for moving the semaphore to one or more "proceed" positions, and means including an electromagnet for holding the 15 semaphore in the position or positions to which it has thus been moved. In some signals of this type the means including the electromagnet is also employed to operationally connect the motor with the semaphore 20 to enable the former to move the latter.

Signals of this character are usually operated by a single source of current, the electromagnet to which I have referred being connected across the entire source while the 25 semaphore is being held in the position or positions to which it has been moved by the motor, as well as at all other times when the magnet is performing any function. When the source of energy is located at an appreciable 30 distance from the signal, or when a battery having a comparatively high internal resistance is employed as the source of energy, the voltage available at the magnet terminals is materially higher when the 35 magnet alone is energized than when both the magnet and motor are energized. On the other hand, the load on the magnet in this type of signal is not as great when the 40 semaphore is being held at rest in the "proceed" position and the motor is disconnected, as it may be at other times, particularly when moving from one position to another. It, therefore, follows that a lower voltage 45 may be impressed on the magnet while the semaphore is being held in the "proceed" position than at other times, with the result 50 that the total energy consumed by the signal is greatly reduced, because, under usual conditions, the total time per day that a signal 55 is held in the "proceed" position is much greater than the time it occupies other positions, and likewise much greater than the time consumed in moving from one position to another by motor energy.

Signals of this type are frequently con-

trolled by a polarized relay in which case the circuit for energizing the motor in moving to the "proceed" position from the "caution" or intermediate position comprises two contacts in series. It is also customary to 60 use graphite for the contact material of one member, at least of each of these contacts in order to insure reliable and certain operation. The resulting contact resistance produces an appreciable fall of potential 65 between the source of energy and the signal when the motor is energized and inasmuch as the motor and magnet are supplied with energy over the same circuit, the voltage at the magnet terminals is still further reduced 70 when the motor is energized and likewise the energy available for actuating the motor is reduced.

One feature of my invention is the provision of a novel means for so controlling the 75 magnet that it is connected across the entire source of operating current at all times while the magnet is functioning except when it is holding the semaphore in the "proceed" position, at which latter time the magnet 80 is connected across a part only of such source, whereby the voltage which is then impressed on the magnet is reduced, with a consequent reduction in the amount of energy consumed by the signal.

Another feature of my invention is the provision of an auxiliary relay controlled by the main signal controlling relay, which auxiliary relay in turn directly controls the supply of current to the motor. The magnet is controlled by the main relay, however, hence the voltage at the magnet terminals is not affected by the drop in potential due to the contact resistance in the motor circuit while the motor is operating. Furthermore, the motor circuit includes only a contact of the auxiliary relay (or several of these contacts in multiple), and consequently the resistance of this circuit is reduced to a minimum.

Another feature of my invention is the use 100 of the auxiliary relay to control the magnet in such manner as to reduce the potential applied to the magnet while the signal is in the proceed position.

I will describe one form of signal embodying my invention, and will then point out the novel features thereof in claims.

The accompanying drawing is a view, 110 partly diagrammatic, showing one form of

railway signal embodying my invention, and one arrangement of controlling circuits and apparatus which may be used in connection with the same.

5 Referring now to the drawing, the reference character S designates a semaphore which is pivotally mounted on a supporting mast or post 33. This semaphore is biased to the "stop" or horizontal position as shown 10 in solid lines, but may be moved to a "caution" or inclined position, and to a "proceed" or vertical position, as indicated in dash lines, by means of an electric motor M through the medium of suitable operating 15 mechanism which I will now describe.

The operating mechanism comprises an arm 34 pivotally mounted at point 34^a and operatively connected with the semaphore S through suitable means indicated by the 20 dash line 46. The arm 34 is moved by chains 37 and 37^a, which chains are in turn driven by the motor M in the direction indicated by the arrows. The chain 37 operates over a sprocket wheel 43 and another sprocket 25 wheel 44, the first of these wheels being driven by the motor through suitable reduction gearing which is not shown in the drawing but which is indicated by the dash line 63. The chain 37^a operates over a 30 sprocket wheel 45 and another sprocket wheel which is not shown in the drawing, but which is mounted directly behind the wheel 44 and is attached to the same shaft as the latter wheel. The chains 37 and 37^a 35 are provided with rollers 38 which project laterally from the chains to engage with a fork 35 pivoted at point 35^a in arm 34. Two pairs of rollers are provided for each chain, the two pairs on each chain being disposed 40 at diametrically opposite points on the chain. The fork 35 comprises three parallel prongs (only one of which is shown), the first and second of which coact with the rollers 38 on chain 37 and the second and third of 45 which coact with the rollers on chain 37^a.

The fork 35 is controlled by an electromagnet D through a toggle mechanism 36 in the arm 34, the control being such that the fork is held rigidly in the position shown 50 with respect to arm 34 when the magnet D is energized, that is, in a projected position in the path of rollers 38, but is free to swing upwardly to a retracted position out of the path of these rollers when the magnet is de- 55 energized. It follows, then, that when magnet D is energized, and motor M drives the chain 37, one pair of rollers 38 on this chain will engage the fork 35 and so elevate arm 34 and semaphore S to the intermediate or 60 caution position, in which position the rollers pass out from under the fork and the fork is caught and held by a latch 41. This latch is pivoted to the frame work of the signal mechanism and is biased to the position 65 in which it is shown by a spring 41^a.

If now the motor M is again operated, the fork 35 will be caught by one of the pairs of rollers on chain 37^a, so that the arm 34 and semaphore S will be elevated to the highest or proceed position, where the rollers will 70 pass out from under the fork and the fork will be caught and held by a latch 42. This latch is biased to engaging position by a spring 42^a. The semaphore will then remain in this position until magnet D becomes deenergized, whereupon the fork 35 will swing upwardly with respect to arm 34 and so becomes disengaged from latch 42, so that the arm 34 and semaphore S will drop to their lowest positions, as shown in 80 the drawing.

Operating current is supplied to the motor M from a battery B, and the electromagnet D is likewise supplied with current by this same battery. The supply of current from 85 this battery to the signal is controlled by suitable means such as a polarized relay A, which relay comprises neutral armature contacts 13, 30 and 25, and polarized armature contacts 18 and 31. The relay A is supplied with current from a battery 47 and is controlled by a pole-changer P in the usual and well known manner.

The supply of operating current to the motor M is controlled by contacts 9 and 49 95 of a relay R in multiple, which relay also at times controls the supply of current to the magnet D by means of a contact 27. This relay R is controlled by a contact member 5, which member is operated by a cam 39, 100 operatively connected with the arm 34. Relay R is also at times controlled by a contact C, which is normally closed but which is opened by a knob 40 on the arm 34 when this arm reaches its highest position. 105

Although I have termed the device R a relay, it may be that in some instances the armature of this relay will be employed to control other elements associated with the signal besides the contacts 9, 49 and 27. 110

The operation of the signal and of the controlling circuits is as follows:

When the relay A is deenergized, the motor M, magnet D and relay R are all de- 115 energized, so that the semaphore S is in the stop position and all of the other parts of the signal are in positions in which they are shown in the drawing. I will now assume that pole-changer P is operated to energize relay A in such direction that the polarized armature contacts 18 and 31 remain open. The closing of the neutral armature contacts of this relay cause magnet D to become energized, the circuit being from the upper terminal of battery B, through wire 12, front 120 contact 13 of relay A, wires 14, 15, and 22, contact 3-2, wire 23, magnet D, wire 4, front contact 25 of relay A, and wire 48 to the lower terminal of battery B. It will be noted that such time magnet D is con- 130

nect with the entire battery B so that the full voltage of this battery is impressed on the magnet. Relay R becomes energized at the same time, its circuit being from the 5 upper terminal of battery B, through wire 12, front contact 13 of relay A, wires 14, 15, 15^a, contact 6—5, wire 16, relay R, wires 17 and 11, to the lower terminal of battery B. The consequent closing of relay R causes 10 battery B to be connected with the operating motor M, the circuit being from the upper terminal of battery B, through wire 8, contact 9 and 49 of relay R in multiple, wire 10, motor M, and wire 11 to the lower terminal 15 of battery B. Motor M and magnet D both being energized, the arm 34 is then raised by the rollers on chain 37, so that the semaphore S is moved to its intermediate or caution position. When this position is 20 reached contact 6—5 is opened and contact 7—5 is closed by the cam 39, so that relay R becomes deenergized and the supply of current to the motor M is, consequently, discontinued. 25 If, now, pole-changer P is reversed so that relay A becomes energized in such direction as to close its polarized armature contacts 18 and 31, relay R will again become energized, its circuit then being from 30 the upper terminal of battery B, through wire 12, contact 13, wire 14, contact 18, wires 19 and 20, contact C, wire 21, contact 7—5, wire 16, relay R, wires 17 and 11 to the lower terminal of battery B. The closing 35 of this relay again supplies current to the motor M through the same circuit as before, so that the chains 37 and 37^a are again operated. Since magnet D is still energized, arm 34 is raised by the rollers on chain 37^a. 40 Shortly after the arm 34 leaves its intermediate position, contact 4—2 becomes closed and contact 3—2 becomes opened, and the magnet D is then energized through the following circuit: from battery B, through 45 wire 12, contact 13, wire 14, contact 18, wires 19 and 26, front point of contact 27 of relay R, wire 28, contact 4—2, wire 23, magnet D, wire 24, contact 25 and wire 48 to the lower terminal of battery B. It will be noted that 50 magnet D is still connected across the entire battery B. When the arm 34 reaches its highest position it opens contact C, thereby deenergizing relay R and so discontinuing the supply of current to the operating motor M. The opening of relay R also opens the circuit which was last traced for magnet D, but the closing of the back point of contact 27 of this relay closes another circuit for magnet D, which circuit 55 is from the middle point of battery B, through wire 29, contact 30, contact 31, wire 32, back point of contact 27 of relay R, wire 28, contact 4—2, wire 23, magnet D, wire 24, contact 25, and wire 48 to the lower 60 terminal of battery B. It will be noted that 65

magnet D is now connected with section b of battery B, so that the voltage impressed on this magnet is considerably reduced. This reduced voltage is sufficient, however, to cause magnet D to hold the fork 35 in 70 engagement with the latch 42 and so to hold the semaphore S in the vertical or proceed position.

It follows from the foregoing, that while the signal is in the proceed position, magnet D consumes less energy than at any other time while this magnet is functioning, and so the total amount of energy required for the operation of the signal is materially reduced. 80

If, while the signal is in the proceed position, pole-changer P is moved to its intermediate position, relay A will become deenergized, so that the circuit for magnet D will be opened, whereupon arm 34 and semaphore S will drop to the positions in which they are shown in the drawing, so that the signal will then indicate "stop". If instead of relay A being deenergized, the pole-changer P is reversed, magnet D will be deenergized, but as soon as the arm 34 drops to the point where contact 3—2 becomes closed, this magnet will again become energized, so that the movement of arm 34 will be arrested when fork 35 reaches latch 41. 90 Magnet D is at such time connected with the entire battery B, so that the energization of the magnet is sufficient to withstand the blow occasioned by the engagement of the fork with the latch 41. 95

Although I have herein shown and described only one form of railway signaling embodying my invention, it is understood that various changes and modifications may be made therein within the scope of the appended claims without departing from the spirit and scope of my invention. 105

Having thus described my invention, what I claim is:

1. A railway signal comprising a semaphore biased to stop position, a motor for moving said semaphore to a proceed position, means including a magnet for connecting said motor with said semaphore and for holding the semaphore in the proceed position, a source of current, a relay for connecting said motor with said source or for disconnecting it therefrom according as the relay is energized or deenergized, means controlled by said relay for connecting said magnet with said entire source of current when the relay is energized and with a part only of said source when the relay is deenergized, and means controlled by the signal for deenergizing said relay when the semaphore reaches said proceed position. 110

2. A railway signal comprising a semaphore S biased to stop position; a motor M for moving said semaphore to caution and proceed positions; means including a mag- 130

- net D for connecting said motor with said semaphore and for holding the semaphore in caution and proceed positions; a source of current B; a relay R adapted when energized to connect said motor with said source of current; a circuit for said relay including a contact 5—6 which is closed while the semaphore is moving from stop to caution position and opened when the semaphore reaches the latter position; a second circuit for said relay including a contact 5—7 which is closed while the semaphore is moving from caution to proceed position and a second contact C opened when the semaphore reaches proceed position; a circuit for said magnet D including said source of current and a contact 2—3 which is closed while the semaphore is moving from stop to caution position; a second circuit for said magnet D including said source of current, a contact 2—4 closed while the semaphore is moving from caution to proceed position, and a front contact of said relay; and a third circuit for said magnet including a part only of said source of current, said contact 2—4 and a back contact of said relay R.
3. A railway signal comprising a semaphore biased to stop position, a motor for moving said semaphore to a proceed position, means including a magnet for holding the semaphore in said proceed position, a source of current, a relay for connecting said source of current with said motor or for dis-

connecting it therefrom according as the relay is energized or deenergized, means controlled by said relay and by the signal for connecting said magnet with a part only of said source when the relay is deenergized and the semaphore is in the proceed position, and means controlled by the signal for deenergizing said relay when the semaphore reaches said proceed position.

4. A railway signal comprising a semaphore biased to stop position, a motor for moving said semaphore to caution and proceed positions, means including a magnet for holding said semaphore in caution and proceed positions, a source of current, means controlled by the signal for connecting said magnet with said entire source of current when the semaphore is in caution position, a relay, means for connecting said magnet with a part only of said source when the relay is deenergized and the semaphore is in the proceed position, and means for energizing said relay while the semaphore is being moved by the motor and for deenergizing said relay when the semaphore reaches the proceed position.

In testimony whereof I affix my signature 60 in presence of two witnesses.

LLOYD V. LEWIS.
